UNITED STATES PATENT OFFICE.

HENRY C. BROWN, OF PHILADELPHIA, PENNSYLVANIA.

CABINET FOR HOLDING TALKING-MACHINE RECORDS.

1,038,841.

Specification of Letters Patent. Patented Sept. 17, 1912.

Application filed May 11, 1910. Serial No. 560,589.

To all whom it may concern:

Be it known that I, HENRY C. BROWN, a citizen of the United States, residing at Philadelphia, in the county of Philadelphia and State of Pennsylvania, have invented 5 an Improved Cabinet for Holding Talking-Machine Records, of which the following is a specification.

My invention is a cabinet designed for 10 holding talking machine records, of different sizes, under pressure, exerted over substantially their entire surface, which will keep them flat, correct warping and avoid rubbing. My improvements are also de- 15 signed to provide for the ready insertion and withdrawal of the records.

A further object of my improvements is to provide a simplified construction.

In the drawings, Figure 1 is a perspective 20 view of a cabinet having my improvements applied thereto; Fig. 2 is a transverse sectional view of the drawer shown in Fig. 1, taken on the line 2—2 of Fig. 1; Fig. 3 is a longitudinal sectional view of the drawer 25 taken on the line 3—3 of Fig. 2; Fig. 4 is a perspective view of a block comprised in the improvements; and Fig. 5 is a perspective view of a detached partition comprised in the improvements.

30 The improvements, as illustrated in the drawings, are used in combination with a casing 1 having the drawer 2. The drawer has in the sides thereof slots 3 which are slightly inclined to the vertical and which 35 receive boards 4 forming backs for supporting the respective sets of portfolios and the records held therein. Longitudinal ribs 5 are formed on the sides near the bottom and longitudinal grooves 6 are formed in the 40 bottom of the drawer.

Separators or partitions 7 are designed to extend transversely across the drawer, and have in the sides thereof recesses or notches 8 for receiving the ribs 5, whereby the separators 45 are movable independently in the drawer without being accidentally removed or displaced in withdrawing or inserting records. In the bottoms of the separators 50 are formed notches 9 adapted for receiving a block 10 having longitudinal bottom ribs 11 which register with the grooves 6, whereby the block is centered, held against lateral movement and permitted longitudinal movement. The back 10' of the block has an inclined surface corresponding to the inclination 55 of the back board 4 against which it

fits; a notch 10" is cut out of the forward part of the block to permit the latter to clear the spring support hereinafter described and engage the front of the drawer, and the top of the block is provided with the cylindrical concavity 12 extending longitudinally of the drawer for the purpose of centering and properly supporting a record of small size.

60 A movable board 13 extends across the drawer in front of each set of separators 7 and is held in place by the engagement of the recesses 14 in the sides thereof with the ribs 5. A recess 15 in the bottom of the board permits the passage of the block 10.

65 Bearings 16 are fixed to the bottom of the drawer in front of the respective boards 13 and support rods 17, the front rod lying in the notch 10" of the block 10. The rods 17 support wire loops 18, having spring coils 19 thereon and ends 20 engaged to the bearings 16, the loops with their connections providing automatically acting levers for pressing the boards 13 and thereby exerting 70 75 an even pressure upon the separators and the records therebetween.

75 As shown, a block 10, is inserted in the forward portfolio. The insertion is readily effected by withdrawing the back 4, pressing the separators forward, inserting the block, and replacing the back, which holds the block securely in place.

80 A set of small disks 21 are adapted to be held between the forward separators upon the block 10, the surface 12 of the latter engaging the correspondingly curved edges of the records, which are centered thereby. Larger sized records 22 are adapted to be placed between separators of the rear set 85 90 and rest directly upon the bottom of the drawer, being held in position by the sides thereof.

95 It will be understood that, for the insertion and withdrawal of a record, separators 100 adjacent thereto can be opened by the insertion of the hand and pushing forward the parts in front thereof, including the spring lever.

The separators are preferably made flexible so that they can be sprung to engage them with and disengage them from the ribs 5.

Having described my invention, I claim:

In a cabinet, a drawer, a back board removably engaged in guides thereof, separators having recesses in the bottoms thereof,

a front board having a recess in the bottom thereof, means for pressing said front board and separators toward said back board, and a block adapted to be inserted in said recesses by the removal of said back board and to be held against the front of said drawer by the engagement of the reinserted back board therewith.

In witness whereof I have hereunto set my name this tenth day of May, 1910, in 10 the presence of the subscribing witnesses.

HENRY C. BROWN.
